UNITED STATES PATENT OFFICE.

EMMETT L. BAILEY, OF WILLIAMSON, WEST VIRGINIA, ASSIGNOR OF ONE-HALF TO
ROBERT L. BAILEY, OF WILLIAMSON, WEST VIRGINIA.

MINE CAR.

1,417,131.

Specification of Letters Patent. Patented May 23, 1922.

Application filed July 24, 1919. Serial No. 312,887.

To all whom it may concern:

Be it known that I, EMMETT L. BAILEY, a citizen of the United States, residing at Williamson, in the county of Mingo and State of West Virginia, have invented certain new and useful Improvements in Mine Cars, of which the following is a specification, reference being had therein to the accompanying drawing.

10 This invention relates to certain new and useful improvements in mine cars, the object being to provide a non-wreckable and non-breakable mine car having its sides constructed of steel and provided with a wooden bottom having the floor planks extended to support the bumper beams.

Another and further object of the invention is to provide a mine car which is exceedingly simple and cheap in construction and one which is very strong and durable, the same being provided with angular sills so arranged that the body proper of the car is supported in a rigid position to withstand the strain to which it is subjected.

25 Another and further object of the invention is to provide a novel form of bumper so constructed that the same is reinforced by the floor planking of the car.

Other and further objects and advantages of the invention will be hereinafter set forth and the novel features thereof defined by the appended claims.

In the drawings—

Figure 1 is a top plan view of a mine car constructed in accordance with my invention.

Figure 2 is a side elevation of the same.

Figure 3 is a front elevation, partly in section.

Figure 4 is a detail view of one of the journal boxes.

Figure 5 is an elevation of one of the journal boxes.

Figure 6 is a detail vertical section through one wall of the car.

45 Referring to the drawings, 1 indicates the side sills which are preferably formed of angle iron and under which are arranged wooden end sills 2, intermediate metal cross bearers 3 and central cross bearers 4 which are preferably formed of T-iron and are extended outwardly to each side, as shown in Fig. 1.

50 Arranged on the sills and cross bearers is a floor sheet formed of wooden planking 5, the ends of which are extended, as clearly

shown, the central plank having an angular member 6 secured thereto forming a bumper.

Extending longitudinally of the car is a draw bar 7 provided with links 8 at its ends, as clearly shown in Fig. 1.

60 The side sills 1 are provided with suitable journal boxes 9 in which are mounted axles 10 provided with wheels 11, one wheel on each axle being fixed thereto and the other being loosely mounted thereon. Said wheels 65 extend upward through openings formed in the planking and are protected by wheel shrouds 12. The axles are supported in the journal boxes by brasses 13, constructed as shown in Fig. 4.

70 Mounted on the structure thus formed is a body provided with vertical sheet steel sides and ends, the upper edges of which carry angle irons 14, said body having corner posts 15 and side standards 16, which are 75 secured to the sheet siding by rivets, as clearly shown in Fig. 6.

Arranged on the planking at each end are angle irons 17 to which the lower edges of the ends are secured, the lower edges of 80 the sides being secured to the vertical flanges of the side sills 1. By this construction a car body is formed having the floor sheet or bottom formed of wooden planking with a steel body in which the side standards are 85 so mounted that an extremely strong support is formed. The car thus formed is provided with an ordinary brake 18 constructed in the usual manner.

90 The side sills are extended outwardly beyond the corner posts 15 and the ends of the planking are cut off obliquely, as shown in Fig. 1, over which are arranged angle irons 19. The wooden end sills 2 are secured in position by braces 20, and arranged in the center in a line with the bumper 6 are blocks 21 which carry angle irons 22 which extend upwardly under the angle irons 6, as clearly shown, in order to produce a support which will withstand the shock of the car, as it is 100 brought into engagement with the bumper of the adjacent car.

105 The angle irons 6 and 22 are secured in position over the blocks 21 and the ends of the central planking of the bottom of the car by bolts 23.

110 From the foregoing description it will be seen that I have provided a mine car with a frame formed of angle irons on which is mounted a wooden bottom carrying a metal

body constructed of sheet steel in such a manner that all of the parts are braced, the upper and lower edges of the body being strengthened by angle irons.

5 What I claim is:

1. A mine car having angular metal side sills and wooden end sills, angular intermediate cross bearers, a wooden flooring arranged on said sills and cross bearers formed

10 of longitudinally disposed planks, a sheet metal body, arranged on said flooring, having corner posts and standards, the planks of said flooring extending outwardly beyond the end thereof, the central plank of said body having an angular member arranged thereon, a filler block arranged between said angular member and the wooden end sill of said car, an angle iron arranged over said filler block extending upwardly under the

15 first mentioned angle iron and a bolt extending through the horizontal portions of said angle irons, filler block and central plank of said flooring.

2. A mine car having a metal frame formed of angular members provided with a wooden bottom formed of longitudinally disposed planks, a sheet metal body mounted upon said bottom, said planking extending

outwardly beyond the ends of said body, angular members arranged over the outwardly extending ends of said planking, the central plank of said body having an angular member arranged thereon, a filler block arranged under said angular member and the wooden end sill of said car and an angular member secured over said filler block by a bolt passing through said angular members and filler block.

3. A mine car having a frame formed of angular members and a bottom formed of planking, said planking extending longitudinally of said car having a body mounted thereon formed of sheet metal, said planking extending outwardly beyond the ends of the body, wooden sills arranged at the ends of said car and a bumper arranged beyond said wooden sills formed of oppositely arranged angular members and a filler block secured together by a bolt extending through said planking, filler block and angular members.

In testimony whereof I hereunto affix my signature in the presence of two witnesses.

EMMETT L. BAILEY.

Witnesses:

R. L. BAILEY,
ROWENA RARDON.
